Primary Examiner — Mitchell I. Siegel(74) Attorney, Agent, or Firm — Rebecca Hanovice; Michael Catania; Sonia Lari(57) CLAIM

The ornamental design for a putter head, as shown and described.

DESCRIPTION

FIG. 1 is a rear perspective view of a first embodiment of the putter head claimed herein;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of the elements on the golf club head are included for the purpose of illustrating unclaimed subject matter and forms no part of the claimed design.
